OIL FEEDER DEVICE

Lomer Lee Richardson, Nutley, N. J.

Application April 28, 1953, Serial No. 351,709

1 Claim. (Cl. 230—206)

This invention relates to an oil feeder device and more particularly to a portable oil feeder device.

The commonly used gas compressors employed in the manufacture of refrigerators and the like are constructed so as to have an oil well container or splash pot wherein the crank shaft of the compressor is disposed. The operation of these compressors, which may be of the one piston cylinder or two piston cylinder type, effects lubrication of the piston by means of the splash effect obtained by the rotation of the piston rod in the oil of the oil well. In the course of prolonged operation, the amount of oil in the oil well diminishes and needs to be replaced. The need for replacement of this oil is infrequent and may be at intervals of about three months more or less. The introduction of small amounts of oil into the splash pot of conventional refrigerating machines has been a cumbersome procedure, which procedure has now been simplified by the use of applicant's oil feeder device of this invention.

According to this invention applicant employs the compressive ability of the refrigerant compressor as well as the pressure of the compressed refrigerant to pump oil from a residual portable reservoir into the splash pot. This introduction of the oil into the splash pot may be done without dismantling or stopping the operation of the compressor. Preferably, however, any back pressure disposed on the surface of the oil in the splash pot is released to the atmosphere so that the oil pumped into the splash pot by the use of applicant's portable reservoir will be introduced into the splash pot against only the pressure of the atmosphere.

This invention will be more clearly understood by turning to the illustrative embodiment shown in the accompanying drawings in which

Fig. 1 is a cross-section of a conventional single cylinder compressor showing, broken away in part, the portable reservoir of this invention.

Fig. 2 is a cross-section of a three-way valve, taken on line 2—2 of Fig. 5, two of which are used in this invention.

Fig. 3 is a cross-section of one embodiment of a portable reservoir used to introduce oil into the splash pot of a compressor.

Fig. 4 is a side view of a different embodiment of this invention showing a structure capable of withstanding high pressure.

Fig. 5 is a top view of a three-way valve used in this invention, and

Fig. 6 is an end view of the three-way valve and showing a closure cap thereon.

Turning to the drawings and particularly Fig. 1, a splash pot 1 having a horizontal base is secured to a piston block 2 by means of bolts 3. A valve block 4 is secured to the top of the piston block 2 by conventional means such as screws (not shown). The valve block 4 is provided with an inlet port or opening and an outlet port or opening. A piston head block 5 having a suction inlet opening and a compressed gas exit opening is dis-

2

posed over the piston block in such a manner that the suction opening of head block 5 is disposed over the inlet port of the valve block with the opening of the head block 5 used for compressed gas being disposed over the outlet port of the valve block 4. Piston head block 5 is secured to valve block 4 by conventional means such as bolts (not shown).

A piston 6 of conventional design is disposed within the cylinder of the piston block 2. A piston rod 7 is secured to the piston and to a crank shaft 8, the latter being substantially centrally disposed in the splash pot 1. The piston rod 7 is provided at its base with a circular cam eccentric 9 adapted to be rotated upon the surface of and into the body of the oil disposed in the splash pot. A pair of three-way valves 10 are secured to the compressor, one of said pair being secured to the head block 5 and the other to a cylindrical tubular pillar 11 communicating with the oil of splash pot 1. The three-way valve connected to the piston head block 5 is secured to that section of the header having a bore hole therein adapted to transport the compressed gas from the outlet valve 12.

Turning to Figs. 2 and 5 the three-way outlet valve has a first bore hole 13 adapted to communicate with the high pressure bore 14 disposed in head block 5. A second bore hole 15 communicates with said bore hole 13 at a right angle, said bore hole 15 being connected to outlet pipe 16. The bore hole 13 also communicates with a third bore hole 17 disposed in spaced relationship to the second bore hole 15. The third bore hole 17 in turn communicates with a threaded valve exit opening 18. A valve stem 19 having a valve block 20 thereon is disposed within the valve 10 in such a manner that it may be actuated to cut off bore hole 13 from communication with bore holes 15 and 17 or it may be actuated so as to permit the high pressure in bore hole 13 to communicate with the outlet opening 18. A threaded pipe 21 is secured to exit opening 18 and an angle cap 22 is in turn secured to said pipe 21.

40 A reservoir container 23, preferably of cylindrical design, is provided with a bottom section 24 preferably welded to the cylindrical section 23. A head plate 25 having a centrally disposed circular opening therein is secured to the top of cylindrical element 23 also by welding or other conventional means. The head plate 25 is provided with threaded bore holes therein adapted to receive threaded rods 26. The head plate is also provided with a circular upright ring section 27.

45 A detachable top plate 27x is secured to said plate 25 by means of wing nuts 28 disposed over threaded rods 26. The detachable top plate 27x is provided with an inlet orifice and an outlet orifice. The inlet orifice is provided with a threaded inlet nipple 29. The outlet orifice is similarly provided with a threaded nipple 30.

50 The detachable top plate 27x is provided with a circular groove. The circular ring section 27 is disposed in the circular groove of the top plate 27x in compressive relationship against a circular packing or stuffing 31. A well pipe 32 is screwed into the outlet opening of the detachable top plate 27 and is of such range as to be in close proximity to the bottom plate 24 of the portable reservoir. Clearly gas pressure introduced through inlet nipple 29 is disposed onto the surface of oil 33, working the oil up through pipe 23 and out of outlet nipple 30.

55 An inlet conduit 34 is disposed between angle cap 22 and inlet nipple 29. An outlet conduit 35 is disposed between outlet nipple 30 and the three-way valve secured to tubular element 11 of splash pot 1. The three-way valves 10 are provided with a pair of apertures 36 adapted to receive bolts for securing said valves to the compressor.

60 In the operation of applicant's portable oil feeder,

conduits 34 and 35 are secured to the pair of three-way valves through their threaded openings 18, the conduit 34 being secured to the three-way valve disposed in co-acting relationship with the high pressure of the outlet valve 12. The other three-way valve 10 is secured to the tubular projection 11 of splash pot 1 so that the high pressure created by the piston 6 disposed in piston block 2 forces the outlet valve 12 to open against its spring 37, forcing the compressed refrigerant gas through bore hole 14 and into inlet conduit 34. The compressed gas is then communicated to the surface of oil 33 forcing the oil through conduit 35 into splash pot 1. It is thus apparent that the refrigerant gas from the refrigerator coils (not shown) is introduced through inlet bore hole 38 of the piston head block 5 and thence through inlet valve 39 into the vacuum chamber formed by piston 6 on the downward or suction stroke of said piston block 6.

Obviously on the compression stroke of piston 6, the compressed refrigerant gas is forced through outlet 12, and when the valve block 20 allows open communication between bore hole 13 and threaded opening 18 the energy of the compression stroke is used to transfer oil from the reservoir of cylinder 23 into the splash pot 1.

While this invention has been described by means of an embodiment thereof, it is not to be limited to this embodiment since other embodiments will become apparent to those skilled in the art upon reading the above descriptive disclosure.

Having described my invention, what I claim and desire to secure by Letters Patent is as follows:

In a compressor adapted to compress refrigerant gas, and having a cylinder block and a piston and piston rod therein, a crank case and a crank therein connected to said piston rod, a valve block and a top plate, said top plate having a bore hole for passage of compressed gas, 35

the improvement comprising a reservoir container for lubricating oil disposed between said bore hole for compressed gas, and said crank case, a first means for connecting said bore hole to said container for introducing compressed gas into said container and consisting of a tubular conduit exterior the compressor and said container, said conduit being adapted to introduce said compressed gas into the top of said container, a vertical well pipe within said container, said pipe opening at its bottom below the surface of said oil, and extending through the top of said reservoir, a second means connecting said crank case to said container for conveying oil from said container into said crank case, and consisting of a valve controlled tubular conduit exterior the compressor and container, and connected to the top of said pipe, a first valve disposed adjacent said bore hole of said top plate, and controlling said first connecting means, and a second valve disposed adjacent said crank case and controlling said second connecting means, whereby compressed refrigerant is used to force oil from said container into said crank case.
